[57] CLAIM

The ornamental design for a spinning toy, substantially as shown and described.

DESCRIPTION

FIG. 1 is a front elevational view of a spinning toy showing my new design, the side opposite being substantially a mirror image;

FIG. 2 is a left side elevational view thereof, the right side being substantially a mirror image;

FIG. 3 is a top plan view thereof; and

FIG. 4 is a bottom plan view thereof.

FIG. 1

FIG. 2

FIG. 3

FIG. 4
